METALLIC END CLOSURE FOR PAPER CARTONS

Joseph M. Frederick, Baltimore, Md., assignor of one-half to Jacob L. Rosenfield, Baltimore, Md.

Application August 14, 1936, Serial No. 96,065

4 Claims. (Cl. 229—43)

This invention relates to receptacles and closures therefor and more particularly to metallic end closures for paper cartons.

Paper cartons provided with metallic end closures are extensively used and in all cases the metallic end closures formed of sheet metal are attached to the paper carton by either a spinning or crimping operation. Where the cartons are of cylindrical form, the attachment of the metallic end closures by these methods at this time present no problem. Where the cartons are multi-sided it is necessary that the edges thereof be rounded and of a substantial radius of curvature in order to permit of the spinning operation. With the use of cartons of this character numerous commercial disadvantages result primarily from the fact that as the cartons are made up in advance the rounded edges thereon do not permit of the folding of the cartons along said edges there being thus required a vast amount of storage space for the same. As paper cartons provided with sharp corners or edges and open at each end will permit of collapsing the same it will be obvious that the same quantity of cartons may be stored in a storage space of considerably less volume.

It is accordingly the principal object of this invention to provide a pre-formed end closure formed as a sheet metal stamping to an open-ended carton having sharp edges or corners and to secure the same to said carton by a simple clamping operation to produce a tight and leak proof connection.

Another object of this invention relates to the manner of forming the metallic end closure.

A further object of this invention relates to the method of assembling the carton and end closure and the manner in which the clamping operation is effected.

With the objects above indicated, other objects of the invention will become apparent as the description thereof given hereunder proceeds with reference to the annexed drawings wherein:

Fig. 1 is a perspective view showing the metallic end closures applied to a carton;

Fig. 2 is a transverse sectional view of one of the attached end closures taken on line 2—2, Fig. 1;

Fig. 3 is a plan view showing one corner of the attached end closures;

Fig. 4 is a plan view of the sheet metal blank from which the end closure is formed;

Fig. 5 is a plan view and Fig. 6 is a cross-sectional view of the blank after the first forming operation thereon;

Fig. 7 is a plan view of the completed end closure and Fig. 8 is a cross-sectional view;

Fig. 9 shows in plan the end closure as applied to the carton and the relationship of the clamping dies; and

Fig. 10 shows the same in section taken on line 10—10, Fig. 9.

In view of the comparative thinness of the sheet metal employed in the end closures and the paper employed in the carton the same have been shown in the various figures of exaggerated thickness.

Referring to the drawings, 10 denotes a carton which may be of paper or other suitable material and in the form shown is of rectangular shape, 10 the sides 11 being of greater width than the sides 12. The carton 10 is made from a flat sheet transversely scored to define the corner edges and with the ends of the sheet overlapped and joined together to form a box with open ends, in the manner well known, and capable of being collapsed to the extent that the same will be flat with the sides engaging each other. This arrangement permits of preforming the cartons (at one place), and storing the same in bundles with the occupancy of a minimum amount of storage space. The end closures 13 are attached to the carton 10 in the manner to be hereinafter described.

The end closure 13 is formed of sheet metal of relatively thin gauge as customarily employed in the manufacture of tin cans, etc., and in its initial form comprises a flat blank 15 having the rectangular shape shown in Fig. 4. The corners 16 of the blank 15 are cut out to provide extensions 17 and 18 which are to be pressed into channel shape as will be hereinafter described. Each extension 17 is defined by an outer portion having a length X and inner portion having a length Y, the respective ends 19 and 20 of which are parallel to each other and joined by an intermediate inclined edge 21. Similar ends 19^a, 21^a and 20^a are provided on the extensions 18, the construction being such that the ends 20 and 20^a intersect, are innermost and at right-angles to each other; the inclined end portions 21 and 21^a are parallel; and the ends 19 and 19^a outermost and at right-angles to each other; the whole forming the cut-out corners 16 as above indicated. This corner construction will permit the ends of the channels to be formed from the extensions 17 and 18, to be mitered so as to come into abutting engagement when the completed end closure 13 is attached to the carton as will be hereinafter described. As is apparent each cut-out corner portion is symmetrical about a diagonal line bisecting the corner with the intermediate end portions 21—21^a parallel to said diagonal line.

The next step in the formation of the end closure 13 is to turn up the edges of the extensions 17 and 18 to form flanges 22 which are of relatively small width and of uniform height throughout their extent.

The last step in the formation of the end closure 13 is to press the extensions 17 and 18 on 60

the blank 15 into channel form to provide respectively the channels 25 and 26. The inside wall 27 of each channel constituted by the inner portion Y is formed normal to the plane of the blank, the outside wall 28 comprising the outside portion X being inclined outwardly as shown in Fig. 8, with the flange 22 directed towards the inside wall 27 and normally spaced therefrom a distance sufficient to permit the entry of the walls or sides of the carton 10. Referring to Fig. 8 it will be observed that the channels are of uniform depth, the walls thereof being joined together in a common plane to one side of the body portion of the blank and parallel therewith. The constructional form of the blank shown in Figs. 7 and 8 comprises the structurally complete end closure 13, which may be finished by a varnished, japanned or enameled operation.

20 The flange 22 serves as a gripping medium and is adapted to be forced into the walls of the carton 10 to securely hold the end closure thereto.

End closures 13 of the character as above described are susceptible of automatic machine attachment to the carton. With the carton held in a vertical position in the automatic capping machine the end closure is positioned over the open end of the carton and through the medium of a plunger die element 30 is forced downwardly so that the edge portions of the sides 11 and 12 of the carton completely enter the channels in the manner clearly shown in Fig. 10, and with the inside channel walls 27 in abutting engagement with the inside surfaces of the carton sides. Arranged exteriorly of the end closure and normally in surrounding spaced relation thereto are four corner dies 31 of right-angle form. Each die 31 has a leg 32 that is one-half 40 the length of the channel 26 and a leg 33 that is one-half the length of the channel 25. The dies 31 are so machined that when the end faces of the legs thereof are in abutting relation the inside dimensions of the rectangle defined thereby will equal the outside dimensions of the carton. Thus, with the end closure fitted over the end of the carton and with the die 30 seated within the enclosure defined by the channels 25 and 26, the outside walls 28 of the channels are 50 forced into engagement with the carton sides 11 and 12 by a simultaneous movement of the dies 31 in the direction indicated by the arrows in Fig. 9, to effect a pressure clamping of the channel walls on the carton sides; the flanges 22 on the outside channel walls being accordingly forced into the surface of said carton sides 55 penetrating the same as clearly shown in Fig. 2.

In view of the thinness of the sheet metal employed in the end closures 13 the outside channel walls 28 will, in the attached position of the same on the carton, lie substantially flush with the outer surface of the carton sides, and in view of the flanges 22 cutting into and penetrating the walls 11 of the carton, the removal 65 of the metallic closure by prying open the channel walls 28 is impossible without destruction of the carton. The above described method of clamping the end closure 13 over the open end of the carton produces a rounded edge 34 at 70 the corners of the end closure, of the same curva-

ture as the very small fillet 35 at the apex of the legs 32 and 33 of the dies 31. This rounding of the corners brings the ends of the channels into abutting engagement and obviates sharp corners which might accidentally cause cuts and tears. Fig. 3 shows enlarged, a corner of the attached end closure.

With one end closure attached to the carton the same may be reversed, the commodity placed therein and the other end closed by a similar end closure in the identical manner as above described.

It is to be understood that end closures of this character may be applied in a similar manner to any shape carton having a plurality of sides 15 such as triangular, hexagonal, etc., as well as to cartons of cylindrical form.

Having thus described my invention, what I claim is:—

1. A metallic closure comprising a sheet metal 20 stamping having a plurality of straight side edges with adjacent side edges thereof arranged at an angle to each other to define a corner, a cut-out portion at each corner symmetrical with respect to a line bisecting said corner, said cut-out portion being defined by diverging inner and outer edge sections, and intermediate edge sections connecting the same and arranged parallel to said line.

2. The metallic closure as specified in claim 1, 30 wherein said inner edge sections of each cut-out portion are of less length than said outer edge sections and are arranged with respect to each other to form a right-angle, said cut-out portions defining a folding portion at each side 35 of said stamping adapted to be folded into a channel, the end edges of said channels by virtue of said cut-out portions being mitered and in juxtaposed relation at each corner of said closure.

3. A receptacle of paper or other fibrous material having a plurality of sides and at least one open end, a metallic closure for said end comprising a unitary sheet metal stamping formed to provide a flat body portion and a substantially vertical channel at each side thereof each channel being adapted to receive therein the entire edge portion of a corresponding side wall of said receptacle, the transverse edges of adjacent channels being mitered and in juxtaposed relation so that in the fastening of the closure to the receptacle by the forced clamping of the channel walls to said edge portions of the receptacle side walls the mitered end edges of said channels are forced into abutting engagement to define solid corners completely covering the corners of said receptacle.

4. In the receptacle as specified in claim 3, 60 wherein each channel comprises substantially vertical inner and outer walls projecting above the plane of said flat body portion, said outer walls being each provided at its lower free edge with an inwardly directed flange adapted to penetrate into the side walls of said receptacle 65 to effect a non-removable attachment of said closure to said receptacle, said outer channel walls lying substantially flush with the outer surface of said side walls.

JOSEPH M. FREDERICK.
